SHARPENER FOR ICE SKATE BLADES

Michael J. Marotta, 85 Plymouth Road,
Manhasset, N.Y. 11030

Filed Oct. 27, 1969, Ser. No. 19,749

Term of patent 14 years

Int. Cl. D8—02; D7—03

U.S. Cl. D8—91

Fig. 1

Fig. 2

Fig. 3

FIG. 1 is a top plan view of the form of the sharpener for ice skate blades, showing my new design;

FIG. 2 is a side elevational view of the form shown in FIG. 1, and

FIG. 3 is a side elevational view of the form shown in FIG. 2 rotated 90°.

I claim:

The ornamental design of a sharpener for ice skate blades, substantially as shown.
